UNITED STATES PATENT OFFICE.

WILLIAM GOLDIE, OF WILKINSBURG, PENNSYLVANIA.

DESIGN FOR A CRATE.

SPECIFICATION forming part of Design No. 31,253, dated July 18, 1899.

Application filed June 17, 1899. Serial No. 720,984. Term of patent 14 years.

To all whom it may concern:

Be it known that I, WILLIAM GOLDIE, a citizen of the United States, residing at Wilkinsburg, in the county of Allegheny and State of Pennsylvania, have invented and produced a new and original Design for a Crate; and I do hereby declare the following to be a full, clear, and exact description of the same, reference being had to the accompanying drawings, o forming a part hereof.

My invention relates to a new and original design for crates and is illustrated in the accompanying drawings, in which—

Figure 1 is a side elevation of the crate. 5 Fig. 2 is a top view. Fig. 3 is an end view, and Fig. 4 is a perspective view as the crate appears when seen from above.

In the drawings similar numerals of reference designate similar parts.

o The leading features of my design consist in a crate having a flat slatted bottom 1 of rectangular form and four upwardly and outwardly extending horizontally-slatted sides 2, which include at their intersection in each of 5 the four corners of the crate an upwardly and outwardly extending corner-piece 3, the cross-section of which is triangular in general out-

line, having its inner face extending diagonally across the corner formed by the intersection of the two sides of the crate. A wedge-shaped groove 3^a, having its sides parallel with the outer faces of the triangular corner-piece, extends throughout the length of the inner face of said upwardly-extending corner-piece. Two horizontal corner-pieces 4, beveled on their inner edges, extend lengthwise the crate along the intersection of its side and bottom and at right angles to the direction of the slats that form the bottom of the crate, as shown in Fig. 2.

My design presents a crate that has a new, distinguishing, and pleasing appearance.

Having described my invention, what I claim as new, and desire to secure by Letters Patent, is—

The design for a crate herein shown and described.

In testimony whereof I affix my signature in presence of two witnesses.

WILLIAM GOLDIE.
